Specification for Design.

Patented July 22, 1913.

Application filed May 13, 1913. Serial No. 767,443. Term of patent 14 years.

To all whom it may concern:

Be it known that we, JOHN D. TOMPKINS and FREDERICK H. FULLER, citizens of the United States, residing at Valatie, in the county of Columbia and State of New York, and Potsdam, in the county of St. Lawrence and State of New York, respectively, have invented a new, original, and ornamental Design for Crimped Paper, of which the following is a specification, reference being had to the accompanying drawing, forming part thereof.

The figure is a plan view of a crimped paper having compressed areas or water marks as shown in our new design.

We claim:

The ornamental design for crimped paper, as shown and described.

JOHN D. TOMPKINS.
